UNITED STATES PATENT OFFICE.

WILLIAM HENRY JOSEPH WILSON, OF KILMARNOCK, SCOTLAND, ASSIGNOR TO SAXONE SHOE COMPANY LIMITED, OF KILMARNOCK, SCOTLAND, A BRITISH COMPANY.

BOOT AND SHOE.

Application filed December 2, 1924, Serial No. 753,447, and in Great Britain October 24, 1924.

This invention relates to improvements in boots and shoes. It is well known that in a boot or shoe having the usual parts connected together in the usual ways, there is 5 the possibility that water from without may get into the boot or shoe by way of the crease which exists along that one of the contours of the boot or shoe along which the top of the welt or of the outer sole is met 10 by the adjacent lower margin of the outside of the upper. It has previously been proposed that an extra strip of leather should be applied to the outside of the crease to close it.

15 It is the object of the present invention to provide for the waterproof sealing of such crease, or of as much of the crease as is forward of the heel or of the "joint" of the boot or shoe, by means and methods different from those which have previously been 20 suggested for the same purpose.

According to the present invention a device for the purpose described, which is to be employed in the manner hereinafter explained, comprises a strip which is formed before application to the boot or shoe, with an upstanding marginal feather along one side. This strip is tapered to a wedge form 25 in cross-section and may be an adhesive strip.

Such a strip may be conveniently produced by skiving one side or margin of a flat strip and bending up a marginal part 30 of the cross-section of the strip through an angle relatively to the rest of the cross-section by passing the strip, for example, between rollers or by subjecting it to any other device which will bend up the feather-edged 35 part of the cross-section.

40 When the strip is in place on the boot or shoe the flat under-face is intended to be bedded, with the aid of an adhesive, upon the top projecting sole-margin which may be the margin of the outer sole of a non-welted boot or shoe or it may be the welt 45 itself in the case of a welted boot or shoe. The upturned marginal feather is to bear closely against and to be made to adhere to the adjacent lower margin of the outside of 50 the upper.

In order that the invention may be more clearly understood it will now be described by way of example only, with the aid of the accompanying drawings, in which—

Figure 1 is a perspective view of a shoe 55 with the strip applied to it;

Figure 2 is a cross-sectional view on an enlarged scale of the strip before the upstanding marginal flange is formed on it;

Figure 3 is a similar cross-section of the 60 strip after the flange has been formed;

Figure 4 is a cross-section through the shoe shown in Figure 1 when it is formed as a welted shoe;

Figure 5 is a view similar to Figure 4 in 65 the case of a non-welted shoe;

Figure 6 is a sectional view similar to Figure 3 of a modified form of strip; and

Figure 7 is a view similar to Figure 4 showing the employment of the strip ac- 70 cording to Figure 6.

Like reference numerals indicate like parts in all the figures of the drawings.

The strip illustrated in Figures 2 and 3 which is to be employed to make the crease 75 weatherproof is a flat strip which is skived to the cross-section shown in Figure 2. The feather-edged margin 1 is then upturned from the body 2 of the strip by passing the strip between rollers or by any other means 80 so that it assumes the shape indicated in Figure 3 prior to its application to the boot or shoe.

In Figure 1 only a portion of the length 85 of the crease aforesaid is covered by the strip, the latter commencing at the point 3 near the heel on the outside and terminating on the opposite side at approximately the corresponding position. A method of making water-proof the desired portion of the 90 length of the crease with the aid of the strip is preferably as follows:—The lower margin of that part of the outside of the lasted upper that is to form one wall of the crease and also that part of the sole 4 in Figure 5 or 95 the welt 5 in Figure 4 that is to form the other wall is coated with an adhesive and the strip is then fed into the crease, having been previously coated with an adhesive upon that face F of the upturned marginal 100 feather which is to contact with the upper, and upon that face G which is to contact with the sole. The angular part A of the cross-section of the strip is then forced well into the crease by means of a blunt tool or a 105 roller, either of which may be taken as being diagrammatically represented at 16 in Figures 4 and 5. This operation is so car-

ried out that the underface of the strip is bedded upon the top of the welt 5 in Figure 4 or sole-margin 4 in Figure 5 so as to cause it to adhere thereto.

5 If it is desired the body 2 of the strip may be additionally or alternatively secured to the welt or sole-margin by stitches specially appropriated to that purpose. On the left-hand side of Figure 4 stitches 6 are shown 10 which pass through the body 2 of the strip, the welt 5 and the sole-margin 4 and these stitches may either be those which serve to stitch the welt to the sole-margin or they may be additional to those stitches. On the 15 right-hand side of Figure 4 the strip is shown as secured in place without the aid of stitches.

Similarly in Figure 5, on the left-hand side the body 2 of the strip is secured by 20 stitches 6 to the sole-margin, the security afforded by these stitches being in this example additional to that of the adhesive.

Alternatively as shown in Figure 6, the strip may be split along its inner side to provide 25 two tapered feathers, an upper or upstanding one 1 as before to be cemented to the outside of the upper, and a lower one 7 to be engaged, as shown in Figure 7, by the inseam stitching.

30 I claim:

1. A method of making weatherproof at least a portion of the length of the welt 35

crease in a welted boot or shoe, which method consists in feeding into the crease a strip of leather having an upstanding marginal feather previously formed along one side, forcing the angular part of the cross-section of the strip and feather well into the crease and securing the strip to the upper by means of an adhesive and to the welt surface. 40

2. A method of making weatherproof at least a portion of the length of the welt 45

crease in a welted boot or shoe, which method

consists in feeding into the crease a strip

of leather having an upstanding marginal

feather previously formed along one side,

forcing the angular part of the cross-section

of the strip and feather well into the crease,

securing the strip to the upper by means of

an adhesive and securing the strip to the

welt surface by stitching. 50

3. A method of making weatherproof at

least a portion of the length of the welt

crease in a welted boot or shoe, which method

consists in feeding into the crease a strip

having an upstanding marginal feather pre-

viously formed along one side, forcing the

angular part of the cross-section of the strip

and feather well into the crease, securing the

strip to the upper and welt surfaces by

means of an adhesive and additionally se-

curring the strip by stitches which pass into

the sole-margin. 55

In testimony whereof I affix my signature.

WILLIAM HENRY JOSEPH WILSON.
